ATTORNEY

UNITED STATES PATENT OFFICE.

MILTON ALBERT RAMALY, OF BOWMANSTOWN, PENNSYLVANIA.

CHAIN FASTENER.

Application filed January 24, 1925. Serial No. 4,518.

To all whom it may concern:

Be it known that I, MILTON A. RAMALY, a citizen of the United States, residing at Bowmanstown, in the county of Carbon and 5 State of Pennsylvania, have invented a new and useful Improvement in Chain Fasteners, of which the following is a specification.

This invention relates to chain fasteners.

The object is to provide a device for 10 fastening the sides of automobile tire chains so as to prevent their becoming accidentally unlocked and detached while in use, said fastener being designed to be permanently secured to one end of the side chain and having 15 means for connection with the other end link, or one of the adjacent links, said connection being easily and quickly made by the mere pressure of the locking member.

Another object is to provide a device of 20 this character which is strong and durable and cheaply constructed without any delicate or complicated parts, the same being arranged and assembled in a manner to avoid the possibility of becoming clogged with or 25 affected by snow, ice or dirt, and being readily operated by the thumb nail to unlock the fastener, when it is desired to adjust or remove the anti-skid chains.

A full and complete understanding of the 30 invention may be obtained from a consideration of the following detailed description taken in connection with the accompanying drawing forming a part of this specification, it being understood that while the drawing 35 shows a practical form of the invention, the latter is not to be confined to strict conformity with the showing thereof, but may be changed or modified, so long as such changes or modifications mark no material 40 departure from the salient features of the invention, as specifically pointed out in the appended claims.

In the drawing, in which similar reference 45 characters designate corresponding parts throughout the several figures:—

Figure 1 is a perspective view of the improved chain fastener shown in open position with the free end of the side chain about to be connected therewith.

50 Figure 2 is a top plan view thereof.

Figure 3 is a top plan view of the device in closed position.

Figure 4 is a vertical, longitudinal sectional view of the device in closed position.

Figure 5 is a vertical section taken on the 55 line 5—5 of Figure 4.

Referring to the drawing there is shown a metallic casing or body member 1 formed of suitably heavy sheet steel capable of being stamped and bent into shape to provide 60 spaced, parallel side walls 2, extending the full length of the body, and joined together along their lower edges by the integral wall or web 3, thus completely closing the space 65 between the side walls along this edge.

At one end the side walls are rounded to provide substantially circular eyes 4, suitably apertured for the reception of a bolt or rivet 5, adapted to receive the spaced end 70 eyes of a chain link 6, said chain being 70 formed in any desired manner, and comprising part of a tire chain or any other chain which it may be desired to connect up.

At their opposite ends, the side plates are 75 further formed into upstanding, rounded eyes 7 formed integrally therewith, and likewise suitably apertured for the reception of another rivet 8, which constitutes a pivot for 80 an elongated locking tongue 9, formed of similar sheet metal and substantially equal in length to the body member, into which the same is adapted to be swung about the aforesaid pivot pin 8.

The side walls are further provided with 85 seats or depressions 10 adjacent to the last-named eyes 7, and at their intermediate portions the side walls are provided along their free, upper edges with inclined portions 11 terminating in vertically disposed shoulders 12, the edges, where connecting 90 the said shoulders to the eyes 4, being rounded on the arc of a circle to constitute seats 13 for a purpose to be explained.

Below the said seats 13, the side walls of the body member are provided with aligned 95 apertures into which is rigidly fixed a transverse pin 14, the ends of which project somewhat beyond the outer faces of said walls, the said pin being substantially on a horizontal plane with the aforesaid rivet or 100 bolt 5.

On each projecting end of the pin 14 there is mounted, exterior to the side walls, a spring coil 15 formed of stiff spring steel wire, said coils being formed intermediate 105 of the ends of a single length of such wire, and joined together by a central loop 16, the side arms of which are located against

the outer faces of the side walls, and the joining bar of the loop passing transversely across the free edges of the side walls within the aforesaid arcuate seats 13 and normally bearing, by reason of the pressure of the coils, against the shoulders 12. The terminal portions 17 of the length of wire constituting the coils and the loop, are directed toward the opposite end of the body member, and are inwardly bent, as at 18, and passed through apertures 19 formed in the side plates, the ends being again bent at right angles to form stops 20 for preventing the accidental removal of the spring members.

The locking tongue 9 is provided in its inner edge, when closed as shown in Figure 4 of the drawing, with an indentation 21 located adjacent to the pivot 8 and into which one of the links 22 at the other end of the side chain is adapted to be seated, as shown in Figure 1, and then, by swinging the tongue 9 about its pivot, to be brought around and seated in the aforesaid seats 10 of the side walls. When strain is then put upon the chain, the pull is exerted against the forward side edges of the ears 7, and at the same time the end of the link bearing against the straight side of the indentation 21, serves to hold the tongue closed, but this is not wholly relied upon to hold the tongue, as other locking means, about to be described, is used to positively hold the tongue in closed position, even though there is no strain on the chain.

The inner edge of the locking tongue is cut away to provide an abutment 23 at the extreme free end of the same opposite the pivoted end, thus allowing space to clear the rivet 5, and at the same time contacting with the bottom wall or web 3 of the body member, to properly align the tongue when fully closed. The under edge of the abutment thus formed is inclined, as at 24, to accord with the aforesaid arcuate seats 13 of the side plates and to allow the loop 16 of the spring member to be moved forwardly in an obvious manner.

At the upper end of the inclined edge 24, there is provided a rearwardly directed seat 25 having a horizontal shoulder 26, which is adapted to snap under the loop of the spring when the tongue is closed and to positively hold the latter in such position. The lower edge 27 of the shoulder is rounded to act as a cam, to automatically force the loop back through the space provided by the seats 13 and the inclined edge 24, said loop then springing, by reason of the spring coils 15, into the seat above the shoulder, as clearly shown in Figure 4 of the drawing, and positively holding the tongue from movement.

The lower or inner edge of the locking

tongue is further provided with a cut-out portion 28 so as not to contact with the aforesaid ends 20 of the terminal portions of the springs.

The link 22, which may be the end link or one adjacent thereto, is applied to the tongue, as shown in Figure 1, after said tongue is swung outwardly into longitudinal alinement with the body member. By closing the tongue, the said link is drawn forward to occupy the opposite seats 10 in the side walls of the body member, thus taking up considerable slack in the side chains of the anti-skid device. As has been stated, the strain of the chain is now imparted to the end eyes 7 of the body member, and as the tongue is further closed, the rounded or beveled edge 27 contacts with the cross bar of the spring loop 16 which forces the latter forward towards the rivet 5 and along the seats 13 until the said cross bar reaches the seat 25 in the tongue, when the same immediately springs behind the shoulder 26 and the tongue is locked. When releasing the same it is only necessary to use the thumb nail, or some small instrument, to force the loop of the spring out of engagement with the shoulder of the tongue as will be readily understood.

From the foregoing it will be seen that a strong and durable fastener has been provided for connecting the ends of tire chains, or other chains, and that the locking member may be easily forced into position to secure the device in place, and manipulated to release the same, without the necessity for any complicated operation or the use of any tools.

What is claimed is:

1. A tire chain fastener comprising a body member having spaced side walls connected at one end to a chain, a tongue pivoted at the other end to close down between the plates, said tongue having a seat provided with a shoulder in its inner edge when closed, a transverse pin traversing the walls beneath said seat and shoulder, a spring having spaced coils adapted to be mounted on the extended ends of the pin and joined by a loop straddling the edges of the plates and engaging the shoulder on the tongue, the free ends of the coils being extended longitudinally along the outer faces of the plates and anchored thereto.

2. A device of the class described, including a body having spaced connected side walls and a pivoted tongue adapted to be closed down between the side walls, said tongue having an inclined, open ended slot in its inner edge when closed, the lower edge of the slot constituting a shoulder having an inclined lower edge, opposite arcuate seats formed in the free upper edges of the spaced side walls and terminating in opposite shoulders, a coiled spring mounted

exteriorly of each of the side walls and joined by a resilient loop traversing the seats in the side walls and normally abutting the shoulders thereof, said loop being
5 forced back away from the last-named shoulders by the inclined lower edge of the tongue and caused to engage over the shoul-

der of the tongue when the same is forced down.

In testimony that I claim the foregoing ¹⁰ as my own, I have hereto affixed my signature.

MILTON ALBERT RAMALY.
